COMBINATION CURTAIN DRAPE AND SHADE FIXTURE MEANS

Filed June 15, 1948

UNITED STATES PATENT OFFICE

2,518,610

COMBINATION CURTAIN DRAPE AND SHADE FIXTURE MEANS

Manuel M. Frank, Sr., and John B. Rodrigues,
Fall River, Mass.

Application June 15, 1948, Serial No. 33,006

1 Claim. (Cl. 248—252)

1

The present invention relates to novel and improved fixture means wherein we combine, in a unique structural assemblage, facilities which adequately serve to enable the user to properly hang and display household curtains, drapes for the curtains, and a spring roller-type window shade.

We are conversant with the state of development of the prior art to the extent that we are aware that it is not new to incorporate, in a single structural adaptation, devices or facilities for simultaneously hanging a window shade, curtains over the shade, and drapes over the curtains. It follows, therefore, that the primary objective in the instant matter is to structurally, functionally and otherwise improve upon multiple purpose hangers and fixtures in the category under advisement.

An object of the invention, structurally speaking, is to provide a pair of telescopically connected sections forming the main hanger frame, these being spring connected and being provided with duplicated brackets or fixtures at opposite ends the outermost ones of which serve to accommodate drapery hangers, the innermost ones of which serve to accommodate and support conventional roller-type window shade, and the intervening ones of which serve to accommodate curtain hangers, the curtain and drapery hangers (not shown) being of conventional types with elbow-ends apertured and properly bent to telescope over and attach to the respective drape and curtain fixtures.

Other objects, features and advantages will become more readily apparent from the following description and the accompanying illustrative drawings.

In the drawings:

Figure 1 is a top plan view of a structural adaptation constructed in accordance with the invention and showing all of the essential features of construction.

Figure 2 is a front elevational view of the structure seen in Figure 1.

Figures 3 and 4 are enlarged cross sections on the lines 3—3 and 4—4 respectively of Figure 2, looking in the direction of the arrows.

Figure 5 is a fragmentary perspective view of an end portion of the improved structure.

Referring now to the drawings by distinguishing reference characters it will be seen that the main part of the structure may be described as an adjustable frame and this is composed of substantially duplicate interconnected and telescopically connected frame sections 7 and 8 respec-

tively. The main telescoping portions of the sections are linearly straight and the opposite end portions are laterally bent, as at 9 and 10 respectively. The body portions of the sections 7 and 8 include well known types of sheet metal channels or guideways 11 and 12 (see Figure 3 for example) and the elbow or bent ends 9 and 10 include similar shorter outstanding channels 13 and 14. As better shown in Figures 1 and 2 there is a cleat or plate 15 fitted between the channels 13 and 14 and rigidly secured in place in any suitable manner and this is provided with an upstanding detent or hook 16 of a substantially well known type and these features 15 and 16 provide a drapery hanger fixture at the right hand end of the structure. Referring now to the main channels 17 and 18 at the opposite or left hand end, the section 7, these have laterally bent channel portions 19 and 20 supporting a cleat 21 with a detent 22. The parts 21 and 22 correspond to the parts 15 and 16 and thus we have sections 7 and 8 of a frame telescopically connected together with interfitting channels and laterally bent end portions 9 and 10 with outstanding plates 15 and 21 having detents 16 and 22 which plates and cleats provide fixtures or brackets for drapery hangers (not shown). The sections 7 and 8 are also provided with lateral lugs 23 and 24 with spurs or pins 25 which are adapted to be fastened in woodwork portions of a window frame in order to properly mount the entire frame structure on the window frame.

We next call attention to the shade (or blind) brackets or fixtures and these are denoted and differentiated from one another by the numerals 26 and 27 respectively. The bracket 26 comprises a plate 28 (see Fig. 4) with a circular hole 29, said plate being formed with a slidable casting or so-called shoe 30 and said shoe having detent lugs 31 slidably mounted in the adjacent channel ways. A set screw 32 is provided and this serves to fasten the casting in a set or fixed position. The fixture 27 is substantially a duplicate of the one just described and comprises an outstanding plate 33 with a notch 34 to accommodate a journal on the window shade roller (not shown) said plate being formed integral with a shoe or casting 35 slidable in the adjacent channel ways 11 and 12 (see Figure 3) by way of outstanding keying lugs 36. Here again we provide a set screw 37 to fasten the shoe in a set or adjusted position.

We next call attention to the curtain hanger fixtures or brackets and these are of L-shaped form and denoted in each instance by the nu-

merals 37. They are duplicates and each includes an upstanding hook 38, the bracket being attached to a sliding plate 39 with a hole 40 for a suitable fastener, if needed. The numeral 41 designates a hook and this serves to accommodate a complementary hook 42 on one end of a coiled spring 43. The coiled spring has its opposite ends attached to the respective hooks 41 and since the plates 39 are rigidly secured to the respective sections 7 and 8, said sections normally hold together under spring action. In other words the sections of the frame are contracted by the take-up action of the coiled spring. Also it will be noted that the shoe portions 30 and 35 of the shade brackets are properly shaped to arch over and accommodate the spring means. Moreover, the spring means resides in intimate contact frame sections 7 and 8 within the space existing between the channel ways of said frame sections.

In practice the frame sections 7 and 8 are spread apart against the tension of the spring means 43 and the spurs 25 on the lugs 23 and 24 are driven into a window frame (not shown) in a suitable manner. Then, the frame is fixed and ready for use and the various fixtures at opposite ends, which are virtual duplicates of one another are ready to accommodate hangers (not shown) carried by the curtains and drapes. For example, the usual elbow-type telescoping members are employed to accommodate the drapes and the elbow ends are fitted over the cleats or plates 21 and 15 and held in place by the detents 22 and 16. The blind or shade brackets 26 and 27 are adjusted to correct positions and the shade roller is suspended in the aperture 29 at one end and notch 34 at the opposite end as is obvious. The shorter cleats 31 with their hooked portions 38 serve to accommodate laterally bent or elbow-ends on telescopically connected curtain hangers of conventional types (not shown). We do not claim the curtain and drapery hangers, on which the curtains and drapes are immediately hung, but simply the structural means, the frame construction and brackets or fixtures which serve to accommodate said hangers.

Changes in shape, size, materials and rearrangement of details and parts may be resorted

to in actual practice, so long as they do not depart from the spirit of the invention or the scope of the appended claim, as is well understood.

Having described the invention, what is claimed as new is:

In a multiple purpose structure of the class shown and described, a frame embodying a pair of complementary frame sections, said frame sections having longitudinal channel portions telescopically connected together, the outer end portions of said frame sections being bent laterally to extend outwardly from the wall or other surface and said end portions being provided with plates and said plates having hooks to accommodate apertured elbow portions on a conventional type drapery hanger means, a base plate rigidly attached to coacting channels on each frame section, an L-shaped bracket mounted on each base plate, said brackets, collectively considered, being adapted to accommodate elbow ends on conventional type curtain hanger rods, a coiled spring attached at its opposite outer ends to the respective base plates and having its major portion confined in close proximity to said frame sections, and a pair of shade brackets, each bracket embodying an outwardly arched shoe provided with a set screw and slidably mounted in the adjacent channels on the coacting frame section, said shoes arching over and serving to partly maintain a coacting portion of the coiled spring in its operative position.

MANUEL M. FRANK, SR.
JOHN B. RODRIGUES.
